(57) **CLAIM**

I claim the ornamental design for a spray/pump head for container, substantially as shown and described.

DESCRIPTION

FIG. 1 is a front elevational view of a spray/pump head for container showing my new design, the rear plan view being a mirror image thereof;

FIG. 2 is a top plan view thereof;

FIG. 3 is a left side elevational view of FIG. 1;

FIG. 4 is a right side elevational view thereof;

FIG. 5 is a bottom plan view thereof;

FIG. 6 is an end section view taken along line 6—6 of the top plan view as in FIG. 2;

FIG. 7 is an end section view taken along line 7—7 of the top plan view as in FIG. 2; and,

FIG. 8 is a front elevational view which shows the non-transparent parts with hatching.

The design is transparent except for the part indicated in FIG. 8 by hatching.

All fine lines, except hatching, express the shape of an inner part which is visible through the transparent surface.
